Primary Examiner — John R Yeh(74) *Attorney, Agent, or Firm* — Williams Intellectual Property; Benjamin F. Williams(57) **CLAIM**

The ornamental design for a scrubbing implement, as shown and described.

DESCRIPTION

FIG. 1 is a front elevation view of my new design;

FIG. 2 is a rear elevation view;

FIG. 3 is a left elevation view;

FIG. 4 is a right elevation view;

FIG. 5 is a top elevation view;

FIG. 6 is a bottom elevation;

FIG. 7 is a diagonal raised front elevation view; and,

FIG. 8 is a longitudinal cross-section view taken along the line 8-8 of FIG. 4.

The broken line in FIG. 4 depicts the sectional line from which the sectional view FIG. 8 is taken and forms no part of the claimed design.
